SHIELDED WATER CLOSET

Sven Duner, Chicago, Ill., assignor to Duner Company, Chicago, Ill., a corporation of Illinois

Application November 22, 1946, Serial No. 711,556

2 Claims. (Cl. 4-8)

1

This invention relates in general to water closets adapted for use in railway cars, other moving vehicles, and the like. More particularly, the present invention relates to novel enclosed hoppers for such water closets.

Vehicle water closets are equipped with operating mechanism comprised of links, springs and/or counterweights, and valves so arranged that when a foot or hand operated lever actuates the mechanism the water closet hopper flushes in a predetermined sequence of operations. As some of these links have rather large relative movements, it is difficult to manufacture a hopper bowl which will encase the operating mechanism and at the same time provide ready access to the linkages for inspection and repairs; therefore, the greater portion of the operating mechanism is placed outside of the hopper bowl. As a result of this exposed position, however, the operating mechanism presents problems in sanitation, cleaning, lubrication, and corrosion.

Previous attempts at shielding of the operating mechanism have not been satisfactory either because of their failure to obtain a complete seal between the shield and the bowl or because access to the enclosed parts has been difficult. If the seal is not a complete one, waste matter and dirt accumulate within the enclosure; consequently, the net effect of the enclosure is one of reduced, rather than increased, sanitation. Other attempts at enclosing the operating mechanism have resulted in structures so difficult to assemble or disassemble that, regardless of their sanitary advantages, they have been discarded for their inherent inaccessibility.

It is a principal object of my invention, therefore, to provide for use in railway cars and the like a shielded water closet hopper wherein the complete enclosure of the operating mechanism facilitates cleaning and maintenance of sanitary standards, reduces corrosion of the parts, and protects lubrication.

Another object is to provide a shielded water closet hopper in which the bowl portion is shaped to permit a complete seal between the bowl and the aforementioned shielding and also to facilitate the positioning and securing of said shielding.

Yet another object of my invention is to provide an enclosed water closet hopper in which the shielding is simple in structure, provides ready access to the operating mechanism, and is attractive in appearance.

Other objects, advantages, and capabilities of my invention will appear in the detailed descrip-

2

tion which follows hereinafter, taken in conjunction with the accompanying drawings, in which:

Figure 1 is a side elevational view of a water closet hopper embodying my invention, in which a part of the shielding has been broken away to reveal parts of the operating mechanism and to show the shape of the bowl portion;

Figure 2 is an exploded perspective view showing a preferred form of one of the shields which encloses the operating mechanism and of the closure plate which is positioned about the actuating lever;

Figure 3 is a detail view taken in vertical section upon the line 3-3 of Figure 5;

Figure 4 is a detail view taken in horizontal section upon the line 4-4 of Figure 1; and

Figure 5 is a perspective view of a preferred embodiment of my invention in the assembled form showing the arrangement of the various parts and the attractive appearance of the assembly.

Like reference characters refer to like parts throughout the drawings and the description which follows.

Referring now more particularly to the drawings, the numeral 6 designates the hopper bowl, which is preferably constructed of vitreous china, although it is understood that any other suitable material may be used. The operating mechanism 7, which controls the dump pan (not shown) during the flushing operation, is placed on the outside of the bowl 6, as best shown in Figure 1. The foot lever 8 is mounted rotatably upon the pinned bracket 9, and actuates the operating mechanism 7 when rotated downwardly.

The operating mechanism 7 is enclosed by the shields 12 and 13, which are positioned against offsets or ledges formed in the hopper bowl 6. The offset on each side of the hopper bowl 6, as shown in Figure 1, is comprised of a vertical component 10, a horizontal component 11, and a connecting portion 18. The contour of the horizontal offsets 11, 11 is best illustrated in Figure 3, while Figure 4 shows a preferred cross-section of the vertical offsets 10, 10. Figures 1 and 3 show a preferred contour of the connecting portion 18.

Figure 2 illustrates a preferred form of the left side shield 12. The slot 14 formed therein provides an opening through which a foot lever 8 projects outwardly. The left side shield 12 is clamped against the pinned support bracket 9 by a closure plate 15 and a standard machine screw 16 which conveniently threads into said support

bracket, the interrelationship of the foregoing elements being best shown in Figure 4. Furthermore, the closure plate 15 restricts the lower portion of the slot 14 against the infiltration of external dirt. The right side shield 13 is secured to a support bracket not shown in the drawing. Except for the slot 14, the right side shield 13 is a mirror image of the left side shield 12; consequently the assembled water closet hopper is symmetrical in appearance.

Both the shields 12 and 13 and the closure plate 15 can be conveniently and inexpensively stamped from sheet metal, preferably a metal having corrosion resistant properties like aluminum or stainless steel. It is also contemplated that the shielding could advantageously be formed of a material such as a synthetic plastic or the like. Further modifications of the contours of the shields 12 and 13 are dictated by the shape of the hopper bowl 6, the location of the operating lever 8, and the placement of the hopper within the water closet compartment. Advantageously the hopper may be placed adjacent a wall or partition as shown in the drawing, thereby eliminating the need of providing shielding for the rear portion of the hopper.

The vertical offsets 10, 10 and the horizontal offsets 11, 11 which are formed on both sides of the hopper bowl 6 make possible a complete, yet simple seal between the shields 12, 13 and said bowl. As shown in the drawings, the vertical and horizontal components of the offsets are joined together by a conjoining portion 18, which both adds to the appearance of the assembly and permits the use of a smaller draw in forming metallic shields. In the preferred embodiment of my invention shown, the offsets are formed so that the edges of the shields 12 and 13 are covered when in place, thereby averting the unsightly appearance and safety hazard of raw, exposed edges. The offsets also provide a supporting ledge against which the shields 12 and 13 may be abutted, thereby increasing the rigidity of the assembly and decreasing the need for other supports. In my invention the number of exteriorly placed supporting elements has been reduced to a minimum, so that continuity of surface is maintained insofar as possible to provide ease in cleaning. Although my invention provides positive sealing of the operating mechanism against external dirt, the shielding is nevertheless so simple in structure that it provides ready access to the enclosed parts. As the two brackets (only left side bracket 9 shown) hereinbefore specified may be conveniently tapped to accept a standard machine screw, it is only necessary to insert or remove two fasteners to either erect or dismantle both shields 12 and 13; hence it is apparent that the operating mechanism of the enclosed water closet hopper as set forth hereinabove may be quickly exposed for inspection or repair.

The routine cleaning of the conventional hopper without shielding is made difficult by the complex structure of the exposed operating mechanism; for that reason cleaning is slow and often perfunctorily accomplished. My enclosed water closet hopper greatly simplifies routine cleaning because only comparatively smooth and extended surfaces are exposed to dirt. Moreover, by enclosing the operating mechanism there is less likelihood of corrosion of the operating mechanism due to frequent exposure to water and cleaning solutions. Still further, in my shielded hop-

per, lubricants applied to the moving parts of the operating mechanism are less likely to be washed away or become contaminated.

While I have shown and described certain embodiments of my invention, it is to be understood that these embodiments have been given by way of example only and that various changes and modifications of the details shown may be made without departing from the spirit of the invention or from the scope of the appended claims.

Having thus fully described and illustrated my invention and indicated its utility, I claim:

1. A sanitary, easily cleaned, water closet hopper for railway cars and the like, consisting of: a water closet bowl having integrally formed therein two substantially vertical offsets and two horizontal offsets, said vertical offsets being respectively positioned opposite one another in the sides of said bowl in the front portions thereof, said horizontal offsets being respectively positioned opposite one another in the sides of said bowl in the upper portions thereof and extending rearwardly from the upper limits of said vertical offsets; a dump pan to empty said bowl during the flushing operation; operating mechanism coacting with said dump pan positioned about the rear portion of said bowl; a foot lever actuating said operating mechanism and extending outwardly therefrom; two support brackets rearwise of said vertical offsets, on opposite sides of said bowl; two formed metallic shields on opposite sides of said bowl abutted against the corresponding offsets, one of said shields secured to its corresponding bracket, the other of said shields having an opening formed therein through which said foot lever extends; and a closure plate positioned beneath said foot lever, said other shield clamped between its corresponding bracket and said closure plate.
2. In a vehicle water closet including operating mechanism for flushing said closet and an actuating lever extending outwardly from said operating mechanism; means for enclosing said operating mechanism to improve the sanitation of said hopper and to facilitate the cleaning thereof, said means comprising: a water closet bowl having a substantially vertical offset integrally formed in each side thereof frontwise of said operating mechanism and a horizontal ledge integrally formed in each side thereof above said operating mechanism and extending rearwardly from the upper end of said vertical offset; two shields, one of said shields on one side of said bowl and the other of said shields on the opposite side of said bowl, said shields being positioned against said vertical offsets and said horizontal ledges, one of said shields having an opening therein through which said actuating lever extends; and means for removably securing said shields in place.

SVEN DUNER.
